US00D936836S

(12) **United States Design Patent** (10) **Patent No.:** **US D936,836 S**
Berkely (45) **Date of Patent:** **** Nov. 23, 2021**

(54) **DENTAL AIR/WATER SYRINGE**

(71) Applicant: **Donovan Winston Berkely**, Irvine, CA
(US)

(72) Inventor: **Donovan Winston Berkely**, Irvine, CA
(US)

(**) Term: **15 Years**

(21) Appl. No.: **29/723,597**

(22) Filed: **Feb. 7, 2020**

Related U.S. Application Data

(60) Continuation of application No. 29/664,288, filed on Sep. 24, 2018, now Pat. No. Des. 875,258, which is a division of application No. 29/583,896, filed on Nov. 9, 2016, now Pat. No. Des. 832,444.

(57) **CLAIM**

The ornamental design for a dental air/water syringe, as shown and described.

DESCRIPTION

FIG. 1 is a perspective view of a dental air/water syringe showing a first embodiment;

FIG. 2 is a left-side elevation view thereof;

FIG. 3 is a right-side elevation view thereof;

FIG. 4 is a front elevation view thereof;

FIG. 5 is a rear elevation view thereof;

FIG. 6 is a top plan view thereof; and,

FIG. 7 is a bottom plan view thereof.

FIG. 8 is a perspective view of a dental air/water syringe showing a second embodiment;

FIG. 9 is a left-side elevation view thereof;

FIG. 10 is a right-side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines shown in the figures represent portions of the dental air/water syringe that form no part of the claimed design. Color and texture may or may not form part of the claimed design or designs without departing from the design disclosed.

1 Claim, 6 Drawing Sheets
